US00D656381S

(12) **United States Design Patent**
Watanabe

(10) **Patent No.:** **US D656,381 S**
(45) **Date of Patent:** **** Mar. 27, 2012**

(54) **CUTTER KNIFE**

(75) Inventor: **Toshiyuki Watanabe**, Osaka (JP)

(73) Assignee: **Olfa Corporation (JP)**

(**) Term: **14 Years**

(21) Appl. No.: **29/375,017**

(22) Filed: **Sep. 16, 2010**

(30) **Foreign Application Priority Data**

Mar. 19, 2010 (JP) ..... D 2010-6823

(51) LOC (9) Cl. **08-03**

(52) U.S. Cl. **D8/99**

(58) **Field of Classification Search** D8/95-99,

D8/107; D22/118; 30/154-162, 329-331

See application file for complete search history.
